UNITED STATES PATENT OFFICE.

MORRIS STEINHARDTER, OF BROOKLYN, NEW YORK.

DESIGN FOR A FIRE-SCREEN.

43,512.

Specification for Design.

Patented Feb. 4, 1913.

Application filed November 5, 1912 Serial No. 729,650. Term of patent 7 years.

To all whom it may concern:

Be it known that I, MORRIS STEINHARDTER, a citizen of the United States, residing at Brooklyn, in the county of Kings, State of New York, have invented a new, original, and ornamental Design for Fire-Screens, of which the following is a specification, reference being had to the accompanying drawing, forming part thereof.

The figure is a plan view of a fire-screen showing my new design.

I claim:

The ornamental design for a fire-screen as shown.

MORRIS STEINHARDTER.
